UNITED STATES PATENT OFFICE.

FREDERICK M. HALL, OF PASADENA, CALIFORNIA, ASSIGNEE TO FLORENCE LOWE BARNES AND WILLIAM STEWART, BOTH OF LOS ANGELES, CALIFORNIA.

CONTROL FOR CONTINUOUS PROJECTORS.

Application filed December 15, 1926. Serial No. 154,886.

This invention relates to a continuously operable motion picture projector, and pertains to mechanism for controlling intermittent operation whereby a selected picture or part thereof may be projected and then stopped to be ready for another cycle of operation. It is an object of this invention to provide mechanism of the character described which requires only attention by the operator for starting the projector, the latter stopping automatically. More particularly, the invention relates to a device adapted to be controlled by a coin or check.

A projector which is arranged to project a picture beginning after the end of a previous projection without requiring rewinding or attention to the film is now practicable. In such machines, an endless strip of film is employed and a single roll upon which and from which the film is wound. Such a device lends itself to control by mechanism which will start the advance of the film and then automatically stop it. However, in the case of a complete picture, it is essential that the film always start and stop at the same place, in order to insure continuity. The present invention has for its primary object the provision of means whereby the travel of the film actuating mechanism a given distance, causes the stoppage of the motive mechanism. Another object of this invention is to provide means of the character just described which includes adjustment to accommodate the machine to film of a variety of lengths. A further object of this invention is to provide a novel coin control mechanism.

These objects together with other objects and corresponding accomplishments are obtained by means of the embodiment of my invention illustrated in the accompanying drawing in which:

Fig. 1 is a side elevation of the control mechanism, parts of the coin chute being shown in section; Figure 2 is a section as seen on the line 2—2 of Fig. 1; Fig. 3 is a section as seen on the broken line 3—3 of Fig. 2 showing the coin trigger; Fig. 4 is a section as seen on the line 4—4 of Fig. 2; and Fig. 5 is a plan view of a section as seen on the line 5—5 of Fig. 2.

Referring with more particularity to the drawing a vertical shaft 6 is provided for positively advancing film for the projecting machine. This shaft is shown in Fig. 1 and may be connected to a variety of mechanisms.

The shaft 6 is journaled in a bearing in a frame 7 and has secured thereto a bevel gear 8. A bevel pinion 9 is in mesh with the bevel gear and is mounted upon a shaft having a driven pulley 10 indicated in dotted lines in Fig. 1. The driven pulley is geared to the drive pulley 11 of an electric motor by means of a belt 13. The motor 12 serves to drive the shaft 6 and thereby move the film or other mechanism. Electric current is supplied to the motor through conductors 14. One of these conductors leads to a switch 15 for controlling the flow of current to the motor. By opening and closing the switch, the motor may be started and stopped. This switch is controlled by mechanism actuatable by a coin or check to close the switch and actuatable by a cam operated from the shaft 6 for opening the switch.

At the end of shaft 6 is a worm meshing with a worm gear 16 mounted upon a shaft 17 journaled in frame 7. Splined upon shaft 17 is a drive gear set comprising three gears marked 18, 19, and 20. A shift lever 21 pivoted at 22 is secured to the gear set by means of a yoke in the manner common with such gears. By means of the shift lever, the gear set may be moved along the shaft 17 to a selected position. A driven shaft 23 has secured thereto in fixed position, three gears 24, 25, and 26, spaced from one another in fixed position upon shaft 23. Gears 24, 25, and 26 are arranged to be meshed with their corresponding gears 18, 19, and 20 respectively, one pair of gears being meshed at a time. Obviously, when gears 20 and 26 are meshed, the speed of shaft 23 will be highest, and when gears 19 and 25 are meshed, there will be an intermediate speed. The lowest speed is obtained with gears 18 and 24 meshing.

Obviously any number of speeds desired, may be obtained by a suitable gear structure. The particular details of the gear structure are not pertinent to the present invention. At the end of shaft 23, is worm 27 meshing with a worm gear 28. Worm gear 28 is fixed to a shaft 29 having a restoring device comprising a cam 30 at the end. With a predetermined number of revolutions of the shaft 6, there will be one revolution of the cam 30. The cam shaft 29 is journaled in brackets forming a part of frame 31.

Pivotedly mounted upon the frame 31 is a lever 32, to the end of which is attached a tension spring 33 tending to move the end 110

of the lever adjacent to the cam downwardly against the cam surface. A pin secures the end of lever 32 to a link 34, and mounted upon the pin is a roller 35 for riding upon the surface of cam 30. Pivotally secured to the upper end of the link is a latch comprising a bell crank trigger 36. The bell crank trigger has an outstanding leg 36^a adapted to engage an abutment. There is a depending leg 36^b having a notch or shoulder 37. A spring 38 tends to move the trigger leg 36^b to the right. Embracing link 34 and trigger leg 36^b is an eye 39 disposed at the end of a lever 40. Lever 40 is pivotally mounted upon the frame 31 at its rear as indicated by 42. The lever is guided in a slot 43 formed in a bracket on the frame and is arranged to limit the travel of the lever. The eye is so disposed that the shoulder 37 of the trigger may be positioned to rest upon the eye. Secured to the lever 40 is a link 44 and at the upper end thereof is a tension spring 45 which is secured to the frame 31. Link 44 is secured to the operating lever 46 of the switch 15. The spring 45 tends to lift the lever 40 and swing the operating lever 46 of the switch to open position. When in lower position the link 34 is in its lower position with roller 35 riding upon the low part of cam 30. Trigger leg 36^b will be so positioned that shoulder 37 is not disposed over the eye 39, and the lever 40 can be moved upwardly except for being held by a keeper. The link 34 and latch constitute a one way catch.

Pivotally mounted between brackets on the frame 31 is a keeper 47, having a shoulder arranged to be disposed over the lever 40. The end of the keeper has an inclined nose 48. A spring 49 tends to hold the trigger with the keeper against or overhanging the lever 40.

It is desirable that latch 36 be actuated when link bar 34 is in its lower position so that shoulder 37 will not overhang eye 39 and thereby hold lever 40 in the position shown in Fig. 2. To this end an abutment 50 mounted upon frame 31 is provided. This abutment has an elongated slot so that the position of the abutment may be adjusted below arm 36^a of the latch. A screw or bolt 51 serves for securing the abutment in selected position.

The device is arranged to be operated by a coin. In Fig. 1, a fragment of a coin chute is indicated by 52. It is arranged so that a coin introduced into the machine will pass downwardly by gravity through the chute 52 and will strike the plate 53 on the end of keeper 47. Spring 49 is selected to have such tension that the impact of the coin on the plate 53 will be sufficient to swing the keeper from its position shown in Fig. 3 so that the keeper will release lever 40. Thereupon spring 45 will raise the lever 40 and

operate switch 15 so as to close the electrical circuit and start the operation of motor 12. The coin after having engaged plate 53, passes into chute 54 and is delivered to a coin receptacle not shown.

Suppose the device has its parts in the position shown in the drawings. In this position, the electrical switch 15 is open and the prime mover 12 is stopped. Normally, at the beginning of operations, the cam 30 will be disposed with its radial side parallel to link 34, and leg 36^b of the bell crank is retracted with shoulder 37 within eye 39. A coin is now introduced into the chute 52 and operates keeper 46 to release lever 40. The spring 45 will tend to swing lever 40 upwardly. The shoulder 37 of the latch 36 is retracted so that eye 39 is unobstructed and may move upwardly over link 34 and leg 36^b until the lever 40 engages the upper part of slot 43. This causes the switch 15 to be closed and starts the operation of the motor 12. The projector is now operated through the shaft 6 and simultaneously shaft 23 is rotated through the intermediate gears. This causes the rotation slowly of gear 28 and cam 30. The roller 35 rides upon the cam and begins to lift the link 34 against the action of spring 33. The parts are so dimensioned that when link 34 is raised by the cam to its highest position, shoulder 37 will clear the top of lever 40 and spring 38 will move the latch so as to project the shoulder over eye 39. When the roller 35 reaches the radial portion of cam 30, link 34 will be pulled to its lower position by reason of the action of spring 33. Due to the engagement of shoulder 37 with eye 39, the lever 40 is swung downwardly causing switch 15 to be opened and the electric motor is stopped. This stops the operation of the projector. Lever 40 may be moved downwardly over the nose 48 of the trigger as best shown in Fig. 3. The keeper 47 is pushed outwardly permitting lever 40 to pass and finally engages the lever 40 by hooking over the same. As the link 34 reaches its low position, the lateral arm 36^a of the catch is engaged by the abutment 50, causing the arm 36^b to be swung inwardly and the shoulder 37 to be retracted, the arm 36^b and shoulder being moved downwardly within the eye 40. In this position, the machine is ready for another cycle of operations.

It will be noticed that there is a positive connection between the projector drive shaft 6 and the means for stopping the motor so that upon a given number of revolutions of the drive shaft, the motor will be stopped. Initiation of the operation of the motor is effected by the coin. It will be observed that the machine may be of a character such that its starting may be initiated manually by pressing downwardly on the keeper 47. Such operation and control may be preferable in

some cases, such as advertising devices and where it is desirable to charge no fee for operation of the machine.

What I claim is:

5. 1. A mechanism for operating a switch comprising a switch operating lever connected to said switch for opening and closing the latter, spring means tending to swing said lever to close said switch, a pivoted trigger 10 having a catch arranged to be hooked over and hold said lever in switch open position, said trigger having an arm for operation thereof at will, spring means tending to hold said trigger in position engaging and holding said lever with said switch open, a one-way catch for said lever including a bar movable longitudinally, a laterally projectable latch on said bar arranged to be projected so as to engage said lever, spring means tending 15 to project said latch, an abutment engageable with said latch to retract the latter at one limit of the bar's travel, spring means tending to move said bar with said latch engaging said lever so as to dispose the latter in switch open position, and a restoring device 20 for operating said bar so as to move the latter longitudinally and then permit return movement upon the latch on said bar being retracted upon the bar engaging said cam at its low point.
- 25 2. A mechanism for operating a switch to control a motor comprising a switch operating lever for opening and closing the switch, spring means tending to swing said lever to close said switch, a pivoted trigger having a catch arranged to be hooked over and to hold said lever in switch open position, said trigger being arranged to be swung at will, spring means tending to hold said trigger in position 30 engaging and holding said lever with the switch open, a one-way catch for said lever including a bar movable longitudinally, a laterally projectable latch on said bar arranged to be projected so as to engage said lever, spring means tending to project said latch, an abutment engageable with said latch to retract the latter at one limit of the device's travel, spring means tending to move said device with said latch engaging said lever so as to dispose the latter in switch open position, and a cam having a surface 35 for operating said bar so as to move the latter longitudinally and then permit return movement, the latch on said device being retracted upon the device engaging said cam at its low point.
- 40 3. A mechanism for operating a switch including a switch operating bar secured to said switch for opening and closing the latter, resilient means tending to move said switch operating bar to close said switch, a trigger 45 for holding said bar in switch open position, said trigger being operable at will to release said bar, a one-way catch engageable with said bar for retracting the latter to switch open position, resilient means tending to move said 50 catch to switch open position and a restoring device for moving said catch to position engaging said bar when the latter is in switch closed position and to hold the latter in such position and operable to release its hold thereon and permit movement of said catch in the opposite direction.
4. Mechanism for controlling a motor by operation of a switch comprising a switch operating bar for opening and closing the 70 switch, resilient means tending to move said switch operating bar to close said switch, a trigger for holding said bar in switch open position, said trigger being operable at will to release said bar, a one-way catch engageable with said bar for retracting the latter to switch open position, resilient means tending to move said catch to switch open position, a cam for moving said catch to position engaging said bar when the latter is in switch 75 closed position and to hold the latter in such position during an interval and then to release its hold thereon and permit movement of said catch in the opposite direction.
5. A mechanism for operating a switch 80 comprising a switch operating lever connected to said switch for opening and closing the latter, spring means tending to swing said lever to close said switch, a trigger arranged to hold said lever in switch 85 open position, said trigger being arranged to be swung at will to release said lever, spring means tending to hold said trigger in position engaging and holding the latter with said switch open, a one-way catch device for said 90 lever including a laterally projectable latch arranged to be projected so as to engage said lever, spring means tending to project said latch, an abutment engageable with said latch to retract the latter at one limit of the device's travel, spring means tending to move said device with said latch engaging said lever so as to dispose the latter in switch 95 open position, and a cam having a surface for operating said bar so as to move the latter longitudinally and then permit return movement, the latch on said device being retracted upon the device engaging said cam at its low point.
6. Mechanism for controlling a switch 105 comprising a switch operating lever connected to the switch for opening and closing the latter, spring means tending to swing said lever to close said switch, a trigger arranged to hold said lever in switch open position, said trigger being arranged to be swung at will and to release said lever, spring means tending to hold said trigger in position engaging and holding said lever with said switch open, a one-way catch device for said 110 lever including a laterally projectable latch arranged to be projected so as to engage said lever, spring means tending to project said latch, an abutment engageable with said latch to retract the latter at one limit, spring 115
- 120
- 125
- 130

- means tending to move said device with said latch engaging said lever so as to dispose the latter in switch open position, and a restoring device for operating said catch device.
5. 7. A mechanism for operating a switch comprising a switch operating lever connected to said switch for operating and closing the latter, spring means tending to swing said lever to close said switch, a trigger arranged to hold said lever in switch open position, said trigger being arranged to be swung at will and to release said lever, spring means tending to hold said trigger in position engaging and holding said lever with said
- 10 switch open, a one-way catch device for said lever including a laterally projectable latch arranged to be projected so as to engage said lever, spring means tending to project said latch, means to actuate said latch to retract the latter, spring means tending to move said device with said latch engaging said lever so as to dispose the latter in switch open position, and a cam having a surface for operating said device so as to move the
- 15 latter longitudinally and then permit return movement.
8. A mechanism for controlling a switch comprising a switch operating lever for opening and closing the switch, spring means tending to swing said lever to close said switch, a trigger arranged to hold said lever in switch open position, said trigger being arranged to be swung at will to release said lever, spring means tending to hold said trigger in position engaging and holding said lever with the switch open, a one-way catch device for said lever including a laterally projectable latch arranged to be projected so as to engage said lever, spring means tending to project said latch, means to actuate 30 said latch to retract the latter at the beginning and end of the device's travel, spring means tending to move said device with said latch engaging said lever so as to dispose the latter in switch open position, and a restoring device having a surface for operating said catch device so as to move the latter longitudinally and then permit return movement.
- 35
- 40
- 45
- 50

In witness that I claim the foregoing I have hereunto subscribed my name this 9th day of December, 1926.

FREDERICK M. HALL.
